Term of patent 14 years

Int. Cl. D26—03, 02

U.S. Cl. D48—31

FIG. 1 is a bottom perspective view of a luminaire showing our new design;

FIG. 2 is an exploded view thereof;

FIG. 3 is an elevational view thereof on a reduced scale;

FIG. 4 is a top plan view thereof on a reduced scale;

FIG. 5 is a bottom plan view thereof on a reduced scale.

The pairs of gusset-like elements, between the reflector and rain shield shown in FIGS. 1 and 2 are repeated at 120° intervals around the vertical center axis of the luminaire.

What we claim is:

The ornamental design for a luminaire, substantially as shown and described.
